NIGHT LIGHT OR SIMILAR ARTICLE

Reginald W. Titmas, Chicago, Ill., assignor to Williams
Plasti-Chemicals Corporation, Chicago, Ill., a corporation of Illinois

Filed June 11, 1964, Ser. No. 80,357

Term of patent 14 years

(Cl. D48—20)

FIGURE 1 is a perspective view of a night light or similar article, embodying my new design;

The dominant features of my design reside in the portions shown in full lines.

I claim:

The ornamental design for a night light or similar article, as shown and described.
